ARCH LIFT ATTACHMENT FOR ICE SKATES

Elmer Anderson, Los Angeles, Calif.

Application August 31, 1938, Serial No. 227,742

3 Claims. (Cl. 280—11.10)

This invention relates to skates, and more particularly pertains to ice-skates of the type in which the skate runners are affixed to shoes.

An object of the invention is to provide a means whereby the arch of the skater's shoe may be adjusted to afford a protuberance interiorly of the shoe such as will act to hold the skater's foot from advancing excessively in the shoe and whereby crowding of the skater's toes into the tips of the shoes will be prevented and thereby obviating a condition which contributes largely to fatigue and discomfort of a skater and thus serves to render the act of skating more enjoyable.

Another object is to provide a device which is adapted to be applied to the ordinary skates of commerce without necessitating any alteration of the skate construction.

Another object is to provide a device of the character described which is adapted to be adjusted to meet varying conditions and whereby the arch of a skater's shoe may be elevated to such point as to conform to or engage and support the arch of the foot of the wearer of the skate to which the device is applied.

A further object is to provide a device for the purpose set forth which is adapted to be produced as an article of manufacture for attachment to the conventional type of combined shoes and ice skates now in use.

With the foregoing objects in view, together with such other objects and advantages as may subsequently appear, the invention is carried into effect as illustrated by way of example in the accompanying drawing in which:

Fig. 1 is a perspective view of a skate, showing the invention as applied;

Fig. 2 is a view in section and elevation of the arch supporting device as detached;

Fig. 3 is a plan view of the device shown in Fig. 2; and

Fig. 4 is a view in section and elevation depicting the mode of operation of the invention.

Referring to the drawing more specifically A indicates generally an ice-skate of the type embodying a shoe 5 having a flexible sole 6 on which latter is mounted in conventional fashion a skate runner 7; the shoe being fitted with a pair of spaced rigid plates 8 and 9 affixed respectively to the heel and toe portions of the sole 6 by means of screws 10 and on which plates the runner 7 is fixedly carried by means of conical columns 11 and 12 projecting from the heel and toe plates 8 and 9 and engaged at their tips with the back 55 of the runner. The forward end of the runner is

upturned and is rigidly connected by a column 13 to the tip portion of the toe plate 9.

In carrying out the invention advantage is taken of the fact that the plates 8 and 9 are arranged on opposite sides of the intermediate portion of the sole 6 which sole by reason of being flexible and slightly elastic, is capable of being bent upwardly into the form of an arch so as to form a protrusion interiorly of the sole of the shoe at the point normally spanned by the arch of the wearer's foot; the invention residing in the provision of an adjustable attachment B adapted to be interposed between the runner 7 and the intermediate portion of the shoe sole 6 and which attachment is so constructed as to be operable to effect a spreading action between the runner and sole so as to elevate the intermediate portion of the latter relative to the runner.

As here shown the attachment B embodies a tubular stem 14 fitted at one end thereof with a yoke or saddle 15 for positioning astride the back of the runner 7, and also embodies a screw threaded shank 16 fixed at one end to a stirrup plate 17 engageable with the shoe sole 6. The free end of the shank 16 extends loosely into the open outer end of the stem 14, and screwed on the shank is an adjustment nut 18 having opposed handles 19 for engagement by the hand or by a suitable tool to facilitate turning the nut on the shank 16. A bearing washer 20 may be interposed between the nut 18 and the outer end of the stem 14.

The stirrup plate 17 is formed with up-turned end flanges 21—22 for projecting over the side edges of the shoe sole to obviate slipping of the plate transversely of the shoe sole.

In order to properly align the stem 14 and shank 16 relative to the runner 7 and at the same time afford a proper seating connection between the shoe sole 6 and the plate 17 the connection between the shank 16 and plate 17 is located closer to one end of the plate than to the other, since in conventional shoe construction, the margins of the intermediate portion of the shoe sole are offset outwardly relative to the general longitudinal center of the shoe and on the plane of which center the skate runner 7 is arranged to extend.

In the application and operation of the invention the attachment device B is initially applied while the yoke 15 and stirrup plate 17 are retracted relative to each other, the yoke 15 being then disposed astride the back of the runner 7 at a point opposite that at or near to the intermediate portion of the shoe sole 6 extending between the heel and toe plates 8—9. The nut 18 is then

turned in a direction to advance the threaded shank 16 and cause the plate 17 to come into contact with the shoe sole 6 and with the flanges 21-22 on the ends of the plate 17 overlying opposed marginal portions of the shoe sole.

The shoe is then applied to the foot of the wearer, whereupon the nut 18 is adjusted on the shank 16 to advance the latter relative to the stem 14 and thereby effect a spreading action between the shoe-sole and the back of the skate runner such as to cause elevation of the flexible intermediate portion of the shoe-sole. This operation is continued until the inner intermediate portion of the shoe-sole is arched to such extent as to closely conform to the arch of the foot of the wearer, and in some instances to slightly elevate the arch of the foot.

This raising of the intermediate portion of the shoe-sole provides an upward protrusion of the intermediate portion of the shoe-sole as indicated at *a* in Fig. 4. This protrusion while acting in effect as an arch support also serves to hold the wearer's foot against longitudinal movement in the shoe and thereby prevents crowding of the wearer's toes into the tip of the shoe, which greatly enhances the pleasure of skating and also lessens the foot fatigue incident to prolonged skating with the toes pinched in the shoe tips.

The device as illustrated in Fig. 2 is adapted to be produced as an article of manufacture which can be readily applied to and removed from the combined shoe and skate construction now generally in use and whereby owners and users of such skates may equip them with the arch support and without making any changes or alterations in the skate and shoe construction.

While I have shown and described a specified embodiment of the invention, it is manifest that it is subject to modification, and accordingly the

invention embraces such changes in construction as come within the meaning and scope of the appended claims.

I claim:

1. As an article of manufacture, an attachment for skates embodying a shoe sole having a flexible arch and a skate runner associated therewith and spanning said arch, comprising a runner engaging yoke, a sole engaging plate, a standard interposed between said yoke and plate, and means for varying the length of said standard; said standard including a tubular stem and a threaded shank freely slideable longitudinally in said stem, and said means for varying the length of said standard comprising a nut screwed on said shank and arranged to bear against an end of said stem. 5

2. An attachment for skates of the type embodying a shoe sole having a flexible arch and a skate runner spanning said arch, comprising a yoke adapted to seat astride the skate runner, a tubular stem fixed on said yoke, a sole engaging plate, a threaded shank carried on said plate and loosely extending into said stem for free longitudinal movement relative thereto, and a nut 10 15 screwed on said shank arranged to bear against the outer end of said stem. 20

3. In an attachment for skates embodying a shoe sole having a flexible arch and a skate runner spanning said arch, a yoke adapted to seat astride the skate runner, a tubular stem on said yoke, an arch supporting plate, a threaded shank carried on said plate and loosely extending into said stem for free longitudinal movement relative thereto, and a nut 25 30 35 screwed on said shank arranged to bear against the outer end of said stem.

ELMER ANDERSON.
